SAILING WATER CRAFT

Walter Andersen, 1443 W. Birchlawn Place,
Ottawa, Ill. 61350

Filed May 19, 1966, Ser. No. 2,359

Term of patent 14 years

(Cl. D71—1)

Fig. 2

FIGURE 1 is a side view of one side of a sailing water craft embodying my design, the side not shown being substantially identical to that shown;

FIGURE 2 is a top plan view thereof;

FIGURE 3 is an elevational view showing the bow of the craft;

FIGURE 4 is an elevational view of the stern; and

FIGURE 5 is a plan view of the bottom.

I claim:

The ornamental design for a sailing water craft, as shown and described.
